UNITED STATES PATENT OFFICE.

GEORGE H. GILMAN, OF CLAREMONT, NEW HAMPSHIRE, ASSIGNOR TO SULLIVAN MACHINERY COMPANY, OF BOSTON, MASSACHUSETTS, A CORPORATION OF MASSACHUSETTS.

DRILLING APPARATUS.

1,250,933.

Specification of Letters Patent. Patented Dec. 18, 1917.

Application filed March 16, 1915. Serial No. 14,740.

To all whom it may concern:

Be it known that I, GEORGE H. GILMAN, a citizen of the United States, and a resident of Claremont, county of Sullivan, and State of New Hampshire, have invented an Improvement in Drilling Apparatus, of which the following description, in connection with the accompanying drawings, is a specification, like characters on the drawings representing like parts.

This invention relates to drilling apparatus, and is more particularly, though not exclusively, concerned with a pressure fluid drilling apparatus of the percussive type.

My invention will be best understood by reference to the following specification, when taken in connection with the accompanying drawings of one illustrative embodiment thereof, while its scope will be more particularly pointed out in the appended claims.

In the drawings:

Figure 1 is a side elevation, partly in vertical section, of a drilling apparatus embodying my invention, a portion of the feed cylinder, the supporting column, and the drill-bit being broken away;

Fig. 2 is a sectional view of the apparatus on line 2—2 of Fig. 1;

Fig. 3 is a plan section, on line 3—3 of Fig. 2;

Fig. 4 is a plan sectional view on line 4—4 of Fig. 1;

Fig. 5 is a detail, longitudinal, vertical section on line 5—5 of Fig. 1;

Fig. 6 is a detail sectional view, on an enlarged scale, on line 6—6 of Fig. 1;

Fig. 7 is a detail, sectional view, on an enlarged scale, on line 7—7 of Fig. 1; and

Fig. 8 is a rear elevation of the parts shown in Fig. 7.

Referring to the drawings, and to the embodiment of my invention which I have selected for illustration, I have there shown a drilling apparatus comprising a drilling tool 10, which may be of any appropriate construction, and which is herein shown supported by the guiding means for forward and backward movement, the same herein comprising a slide 11 and a guide 12 therefor, the slide being fixedly secured to the rear end of the drilling tool. In the specific example herein shown, the slide 11 and guide

12 are in the form of telescopically arranged piston and cylinder members, and may be utilized as a feeding means to advance or 55 retract the tool. The drilling tool and its guiding means thus constitute a unitary structure, which is mounted on a novel supporting mechanism which I will now describe.

A suitable support 13, herein in the form 60 of an upright column having a jack screw 14 of common form, whereby it may be fixedly secured by engagement with the roof and floor of the mine in the customary manner, is provided with a laterally extending 65 arm 15, having a clamp comprising clamping members 16 and 17, provided with clamping bolts 18, whereby it may be secured to the column 13 at an appropriate height. To the rigid support as thus constituted, the 70 drilling tool and its guiding mechanism are connected by parallel-motion mechanism, which permits the tool to move in any direction in a plane transverse to its axis. The mechanism also includes means permitting 75 the tool to be adjusted angularly in any direction. This alining mechanism may take other forms, but in the present embodiment thereof, comprises an arm 19, mounted to swing in a generally vertical plane about 80 the axis of a suitable pivot, herein in the form of a stud 20, projecting from an appropriate saddle 21 affixed to the rigid arm 15 by a clamp collar comprising two clamping members 22 and 23, provided with clamping bolts 24, whereby the collar may be secured at the desired point on the rigid arm 15, and adjusted about the axis of the latter. Herein, the saddle 21 is provided with a flange 25, and the arm 19 is provided with 85 a similar flange 26, the two being adjusted face to face, and being sufficiently large in diameter to constitute an appropriate bearing surface which will receive the thrust of the tool, and permit the latter to turn easily about the axis of the stud 20. If desired, there may be provided means for varying the frictional resistance by causing one disk to bear with greater or less degree of pressure against the other, such means in the 90 present instance comprising a hand-nut 27, having screw-threaded engagement with a reduced portion 28 of the stud 20, a helically coiled spring 29 encircling the reduced por-

tion 28, bears at one end against a shoulder 30 on the stud, and at its other end against a washer 31, interposed between the nut 27 and the arm 19, said spring being arranged 5 to cause the disk 26 to recede from the disk 25, to lessen the friction when the nut 27 is turned in the proper direction.

It will now be apparent that the swinging arm 19 constitutes a species of pendulum, 10 by which the drilling tool is suspended from the fixed support to swing about an axis extending in a general direction parallel to its own. It should here be noted that the tool, in swinging about such axis, is capable of 15 accommodating itself automatically to lateral changes of alinement of the drilled hole, as the drilling operation proceeds.

As a means for permitting the drilling tool to be adjusted in a vertical direction as 20 the drilling operation proceeds, the arm 19 is herein made in the form of two telescopically arranged members 32 and 33. It will now be evident that by use of this telescopic and swinging connection of the arm with 25 the support, the tool is permitted to move in any desired direction in a plane transverse to its own axis.

Should it be desired to manually adjust the telescopic connections as described, appropriate means may be employed for that 30 purpose, such for example as a rack 34 and pinion 35. As herein shown, the rack is carried by the member 33, and the pinion is secured to a shaft 36, journaled in suitable 35 bearings provided in ears 37 and 38 projecting laterally from the member 32. The telescopically arranged members may be secured in the desired position of adjustment by suitable means, herein connected to the 40 pinion 35 to lock the latter against rotation, whereby the rack is locked against lengthwise movement. As herein shown, the shaft 36 is provided for this purpose with a projecting terminal portion 39, on which a hand 45 lever 40 is fulcrumed at 41. This hand lever is provided with suitable means, normally to hold the shaft against rotation, but permitting the same to be released at will, and rotated by the use of the hand lever. For 50 this purpose, the latter is herein provided with a tooth 42, which is adapted to enter any one of a series of depressions 43 in an outer face of the ear 38, whereby in any one of a plurality of predetermined positions 55 of adjustment, the pinion may be positively locked.

As a means for normally maintaining the locking engagement of the tooth with the selected depression, the hand lever 40 herein 60 carries a spring 44, which, by acting against a pin 45, presses the latter against the outer face of the ear 38, and reacting upon the lever, moves the handle portion in an outward direction. The locking engagement

may be interrupted by simply pressing the 65 handle of the lever inwardly, whereupon the same may be employed to turn the pinion for the purpose of adjusting the telescopic members, after which the release of the handle causes the parts to be locked in the selected 70 position of adjustment.

Brief reference has already been made to the use of means for permitting the drilling tool to be adjusted angularly to compensate for changes in direction of the drilled hole, 75 as the drilling operation proceeds. This may be accomplished by the use of a universal joint of suitable construction, herein exemplified by ball and socket members 46 and 47. The latter may be conveniently formed, 80 in part at least, on the lower end of the member 33, to constitute a collar. As herein shown, this collar is formed in two parts 48 and 49, pivotally connected to each other by a stud 50, whereby they may be opened 85 to receive or to release the ball member, and whereby they may be caused to confine the latter with the requisite degree of friction to resist to a greater or less degree turning movement of the ball member within the 90 socket member. To this end, two portions of the collar are connected to each other at a point substantially opposite their pivot by a clamping bolt 51, hinged at 52 to the member 48, and having a nut 53, whereby the 95 clamping action may be varied. If desired, this nut may be provided with a grasping handle 54, to obviate the use of a wrench.

If desired, the described clamping means may be utilized additionally to hold the 100 cylinder 12 against axial movement with relation to the ball member, the latter for this purpose being herein provided with a plurality of slots 55, whereby it is rendered to a certain extent extensible and contractible, 105 and may be contracted by the use of the clamping collar, thereby to clamp the cylinder firmly in place.

By simply loosening the clamping means, the cylinder may be moved axially with relation to the ball member for the purpose of adjusting the drilling tool for different 110 lengths of drill steel. This may be conveniently accomplished by holding the drilling tool fixed and applying air to the front or rear end of the feed cylinder, as the case may be, to cause the latter to be moved in the desired direction and to the proper extent. During this adjusting operation, the drilling tool may be conveniently held in 115 fixed position by causing the drilling steel to be cramped in the drill hole, thereby affording the desired degree of resistance to permit the feed cylinder to be moved one way or the other, after this clamp has been 120 loosened.

It should now be apparent that the drilling tool is supported by a parallel-motion

mechanism and a universal connection, whereby it is capable of a perfect freedom of adjustment in either direction within certain reasonable limits, and that therefore 5 the machine is enabled to accommodate itself, or be readily adjusted, to changes in direction or alinement of the drilled hole as the drilling operation proceeds, thus leaving the operator free to give his attention to 10 other matters, such for example as another drilling machine, or the removal of the debris known as "mucking". This arrangement, moreover, facilitates the changing of drill steels, because this may be accomplished by simply offsetting the machine with relation to the drilled hole and removing the drill steel from the latter, without otherwise disturbing the machine. The latter possesses still another advantage, that 15 of permitting the drilling of holes very close 20 to a wall extending in a general direction parallel to the axis of the machine, this being arranged possibly by the offset arrangement of the drilling tool with relation to 25 the pivot on which it is hung.

The drilling tool itself may be of any other appropriate construction, but is herein 30 of the pressure-fluid actuated type, having a cylinder 56 within which a piston 57 is mounted to reciprocate. The piston may 35 actuate a drill-bit 58 in any appropriate manner, but is herein provided with a reduced portion 59 constituting a hammer bar extension arranged to deliver a rapid succession of blows upon the drill-bit, or upon 40 a striking pin 60, the drill-bit being held loosely by a chuck 61 having a suitable rotating mechanism 62. The piston is herein reciprocated under the control of a suitable 45 distributing valve 63 mounted in the valve casing 64 having a pressure supply space 65, from which pressure fluid is delivered alternately to ports 66 and 67 at the front and rear ends respectively of the cylinder.

The cylinder 56 is herein provided with a rear cylinder head 68, to which is rigidly attached the forward end of the piston 12, or its piston rod 69. The feeding device 50 may be of any suitable character, but herein the slide 11 and piston 12, as already indicated, constitute the piston and cylinder of a pressure-fluid operated feeding mechanism. The specific construction and mode of operation of the feeding mechanism is not essential 55 to the present invention, and it may, therefore, be stated that any one of many suitable well-known devices of this character can be used, but for this purpose of illustration, I have shown one in which the piston rod 69 is provided with a pressure fluid passage 70, which leads to the rear end of the feed cylinder, and a pressure fluid passage 71, which leads to its front end, both being under the control of a valve 72 pro-

vided with a passage 73 for the supply of 65 pressure fluid to one end of the cylinder, and a passage 74 for exhausting the pressure fluid from the opposite end of the cylinder through an atmospheric vent 75. It should be understood, however, that other 70 forms of feeding mechanisms may be employed to advantage.

While I have herein shown and described one form or embodiment of my invention for illustrative purposes, and have disclosed 75 and discussed in detail the construction and arrangement incidental to one specific application thereof, it is to be understood that the invention is limited neither to the mere details or relative arrangement of parts, nor 80 to its specific embodiment herein shown, but that extensive deviations from the illustrated form or embodiment of the invention may be made, without departing from the principles thereof.

Having thus described my invention, what I claim and desire by Letters Patent to procure is:—

1. A drilling apparatus comprising, in combination, a drilling tool, a support, and 90 connections between said tool and said support including a universal joint permitting the direction of the tool's axis to be changed, a pivot by which said tool is mounted to swing about an axis extending in the same 95 general direction as that of said tool, and means permitting the axis of said tool to be rectilinearly adjusted toward and from said pivot.

2. A drilling apparatus comprising, in combination, a drilling tool, a support, and 100 connections between said tool and said support including a universal joint permitting the direction of the tool's axis to be changed, a pivot by which said tool is mounted to 105 swing about an axis extending in the same general direction as that of said tool, and means for rectilinearly adjusting the axis of said tool toward and from said pivot.

3. A drilling apparatus comprising, in 110 combination, a drilling tool, a support, and connections between said tool and said support including a universal joint permitting the direction of the tool's axis to be changed, a pivot by which said tool is mounted to 115 swing about an axis extending in the same general direction as that of said tool, means permitting the axis of said tool to be rectilinearly adjusted toward and from said pivot, and means to secure said tool in the 120 desired position of adjustment.

4. A drilling apparatus comprising, in combination, a drilling tool, a support, and 125 connections between said tool and said support including a universal joint permitting the direction of the tool's axis to be changed, a pivot by which said tool is mounted to swing about an axis extending in the same

- general direction as that of said tool, and telescopic means interposed between said joint and said pivot and permitting the axis of said tool to be rectilinearly adjusted toward and from said pivot.
5. A drilling apparatus comprising, in combination, a drilling tool, a support, and connections between said tool and said support including a universal joint permitting the direction of the tool's axis to be changed, a pivot by which said tool is mounted to swing about an axis extending in the same general direction as that of said tool, and means comprising a rack and pinion for rectilinearly adjusting the axis of said tool toward and from said pivot in a direction transverse to the axis of said tool.
10. Drilling apparatus comprising, in combination, a percussive tool; a fixed support therefor; a pivoted arm extending in a direction transverse to the axis of the tool operatively interposed between said support and said tool and adapted to swing about an axis extending in the same general direction as the axis of said tool; and a universal joint interposed between said arm and said tool, whereby said tool may swing about said arm, or change its angular relation to said pivot thereby accommodating itself to changes in direction of the drilled hole.
15. A drilling apparatus comprising, in combination, a drilling tool, a support, and connections between said tool and said support including a universal joint permitting the direction of the tool's axis to be changed, a pivot by which said tool is mounted to swing about an axis extending in the same general direction as that of said tool, means comprising a rack and pinion for rectilinearly adjusting said tool toward and from said pivot, and means for securing said pinion against rotation.
20. Drilling apparatus comprising, in combination, a drilling tool, a support, and connections between said tool and said support including a universal joint permitting the direction of the tool's axis to be changed, a pivot by which said tool is mounted to swing about an axis extending in the same general direction as that of said tool, means comprising a rack and pinion for adjusting said tool toward and from said pivot, means for securing said pinion against rotation, and a single means for turning said pinion and operating said securing means.
25. A drilling apparatus comprising, in combination, a drilling tool, feeding means therefor; a support; and mechanism connecting said drilling tool and its feeding means to said support including a universal joint by which said tool and its feeding means are rendered angularly adjustable, a pivot by which said tool and its feeding means are mounted to swing about an axis extending in the same general direction as the axis of said tool, and telescopic means permitting the axis of said tool and its feeding means to be adjusted toward and from said pivot while said telescopic means maintains the direction of the axis of the tool.
30. Drilling apparatus comprising in combination, a percussive tool; a fixed support therefor; and a pivoted arm extending in a direction transverse to the axis of the tool operatively interposed between said support and said tool and adapted to swing about an axis extending in the same general direction as the axis of said tool; and a universal joint interposed between said arm and said tool whereby said tool may swing about said arm, move toward or away from said arm, or change its angular relation to said pivot thereby accommodating itself to changes in direction of the drilled hole.
35. A drilling apparatus comprising, in combination, a hammer drill, pressure fluid feeding means therefor axially aligned therewith, the ball and socket members 46 and 47 engaging said pressure fluid feeding means, the longitudinally extensible arm 32-33; the pivotal support 20-26 extending in the same general direction as the axis of the drill and operatively connected to a fixed support, the whole apparatus being organized and operating substantially as described.
40. Drilling apparatus comprising, in combination, a percussive tool, pressure fluid feeding means therefor, the longitudinally extensible arm 32-33; the pivotal support 20-26 for said arm extending in the same general direction as the axis of said percussive tool, and rack and pinion means 34-35 for producing extension or contraction of said extensible means.
45. Drilling apparatus comprising, in combination, a percussive tool, pressure fluid feeding means therefor in alinement therewith, the longitudinally extensible support 32-33 having two longitudinally relatively

extensible members held in non-rotating relation to each other, said feeding means being connected to one of said members; a pivotal support having a pivot extending 5 in the same general direction as the axis of said percussive tool and connected to the other of said extensible members, substantially as described.

In testimony whereof, I have signed my name to this specification, in the presence of 10 two subscribing witnesses.

GEORGE H. GILMAN.
